OF D. 15,437

DESIGN.

H. HUNT.

CARPET.

No. 15,437.

Patented Oct. 7, 1884.

UNITED STATES PATENT OFFICE.

HENRY HUNT, OF GREENVILLE, NEW JERSEY, ASSIGNOR TO THE HARTFORD CARPET COMPANY, OF HARTFORD, CONNECTICUT.

DESIGN FOR A CARPET.

SPECIFICATION forming part of Design No. 15,437, dated October 7, 1884.

Application filed August 6, 1884. Term of patent $\frac{3}{4}$ years.

To all whom it may concern:

Be it known that I, HENRY HUNT, of Greenville, New Jersey, have invented a new and original Design for Carpets, of which the following is a specification, reference being had to the accompanying photograph, which forms a part of the same.

The invention relates to a design to be worked into or upon surfaces, such as carpets or similar fabrics; and it consists in the novel configuration and grouping of figures herein specifically shown and claimed.

The accompanying photograph is a face view of a carpet showing my new design.

The design consists of large open-flower figures and prominent flag and oak leaves, arranged along inconspicuous stem-connections, but evenly and closely filling the entire face of the design.

The photograph clearly shows the design in all its details.

I claim—

The design for a carpet, substantially as shown and described.

HENRY HUNT.
